UNITED STATES PATENT OFFICE

WILLIAM E. BARTEL, OF WALTHAM, MASSACHUSETTS, ASSIGNOR TO JUDSON L. THOMSON MANUFACTURING CO., OF WALTHAM, MASSACHUSETTS, A CORPORATION OF MASSACHUSETTS

TWIN-RIVET-SETTING MACHINE

Application filed March 26, 1928. Serial No. 264,643.

- This invention relates to a machine for setting rivets, the object of the invention being to provide a machine that will set two rivets at the same time.
- 5 The invention relates particularly to the mechanism which feeds the rivets into position so that two reciprocating plungers or drivers may set two of the rivets at the same time. The rivets are fed by the improved feeding device from a primary raceway alternately to two secondary raceways located upon opposite sides of the primary raceway.
- 10 The invention consists in the combination and arrangement of parts set forth in the following specification and particularly pointed out in the claims thereof.

Referring to the drawings:—

Figure 1 is a front elevation of a twin rivet setting machine embodying my invention, the same being broken away to save space.

Fig. 2 is a left hand side elevation of the same also broken away.

25 Fig. 3 is a sectional elevation taken on line 3—3 of Fig. 1, illustrating one of the drivers and a portion of one of the rivet carriers, together with one of the secondary raceways and the primary raceway.

30 Fig. 4 is a sectional elevation taken on line 4—4 of Fig. 1.

Fig. 5 is a plan view of the rivet feeding slide.

Fig. 6 is a detail sectional elevation viewed from the front of the machine illustrating the rivet feed slide positioned in a portion of the frame of the machine.

Like numerals refer to like parts throughout the several views of the drawings.

40 In the drawings, 10 is the frame of the machine. 11 is the rivet hopper which is operated in a manner well known to those skilled in the art, to feed rivets to a primary raceway 12. The rivets pass down the raceway 12 until they arrive at a rivet carrier slide 13. The rivet carrier slide 13 has a flange 14 extending laterally therefrom along its lower edge. This flange is slotted to form T-shaped slots 15 and 16. The shank 50 of the rivet, when it is positioned upon the

slide 13, projects into the narrow portion 17 of the slot 15, or into the narrow portion 18 of the slot 16, while the head projects into the enlarged portion 19 of the slot 15 or into the enlarged portion 20 of the slot 16.

When the rivet has passed down the primary raceway 12 to the bottom thereof, it drops into one of the slots 15 or 16, according to the position of the slide 13. As illustrated in the drawings, Fig. 1, the rivet which is about to be fed toward the left, Fig. 1, is shown as resting in the T-shaped slot 15.

The slide 13 has a reciprocating motion imparted thereto by a lever 21, pivoted at 22 to the frame of the machine and having a pin 23 fast thereto and projecting laterally therefrom into a slot 24 provided in the carrier slide 13. A rocking motion is imparted to the lever 21 by another lever 25 and by a spring 26 which connects the lever 25 to an arm 27 on the lever 21, the spring being connected to the arm 27 by a pin 28 and to the lever 25 by a pin 29. The lever 25 is pivoted at 30 to the frame of the machine and its upper end has an inclined edge 31 thereon which bears against a friction roll 32 rotatably mounted on a block 33 the friction roll 32 thus constituting a contact member. A spring 34 holds the inclined edge 31 of the lever 25 against the friction roll 32. The block 33 is fastened to a rod 35 which extends through the outer end of a lever 36 pivoted at 37 to the frame of the machine and to which a rocking motion is imparted by a crank, not shown in the drawings.

The lever 36 is slotted at 38 and 39 to receive the upper ends of plungers 40 and 41, through which the rod 35 projects. The plungers are alike, and the plunger 40 is illustrated in detail in Fig. 3, said plunger being mounted to slide in a sleeve 42 and terminating at its lower end in a driver 43 which is in alignment with a median line of a rivet carrier 44 and anvil 45 which is supported upon an arm 46 forming a portion of the frame of the machine. The rivet carrier 44 consists of two fingers 47 and 48 which are supported by spring-actuated members 49 and 50 upon a slide 51. The slide 51

is integral with the sleeve 42 and is moved upwardly to stop against the frame by a spring 52. The rivet carrier 53 and the plunger 41 are the same in construction as the rivet carrier 44 and plunger 40 and are 5 operated in the same manner.

The rotatable member of the hopper 11 has an intermittent feeding movement imparted thereto by a link 54 which is connected by a 10 pin 55 at its lower end to a block 56 which is fastened to the rod 35. The upper end of the link 54 is pivotally connected to a rocker arm 57 upon which is pivotally mounted a pawl 58 which actuates a ratchet 59 fast to a shaft 60, to which the rotary member of the hopper 11 is fastened, this rotary member of the hopper being well known to those skilled in the art, but not shown in the drawings.

The general operation of the mechanism hereinbefore specifically described is as follows:—Assuming a rivet 61 to be positioned in the carrier 44 and another rivet 62 to be positioned in the carrier 53, the plungers 40 and 41 will be moved downwardly engaging the rivets 61 and 62 and moving them downwardly, together with their carriers 44 and 53, until the rivets pierce a piece of sheet material 63 shown in Fig. 1, and are clinched against the sheet material by the anvils 45 and 45'. During this downward movement 20 of the plungers, the lever 25 will be rocked so as to rock the lever 21 toward the left Fig. 1, moving the slide 13 from the position illustrated in Figs. 1 and 5 toward the left, 25 until the median line of the slot 15 is brought into alignment with the median line of a secondary raceway 64, whereupon a rivet 65 carried by the slide 13 will drop out of the slide and slide down the secondary raceway 64 until it engages the right hand edge 65' of the 30 plunger 40. The plunger at this time having moved downwardly to engage the rivet 61 on the rivet carrier 44.

When the rivets have been set, as hereinbefore set forth, and the plungers moved upwardly, the rivet 65 will drop into the carrier 44 as soon as the lower end of the driver 43 is moved upwardly so as to clear said rivet.

On the upward movement of the plungers, 50 the lever 21 will be rocked toward the right moving the slide 13 from its extreme position at the left, Fig. 1, to its extreme position at the right, that is, to the position illustrated in Fig. 1. This movement of the slide 13 will carry another rivet from the primary raceway to another secondary raceway 67, the last-named rivet having dropped into the slot 16 when the median line of the slot 16 was brought into alignment with the median line 55 of the primary raceway and that occurred when the median line of the slot 15 was brought into alignment with the median line of the secondary raceway 64.

When the rivet has been brought from the 60 primary raceway to the secondary raceway

67, the plunger 40 is in its uppermost position and the rivet will therefore slide down the secondary raceway 67 and drop into its pocket 53, thus the rivets will be alternately fed by the slide 13 from the primary raceway 12 to the secondary raceways 64 and 67 and will be simultaneously driven and clinched by the plungers 40 and 41.

The distance between the median lines of the slots 15 and 16 is the same as the distance 75 from the median line of the primary raceway 12 to the median line of either of the secondary raceways 64 or 67.

I claim:

1. A twin rivet setting machine having, in combination, a primary raceway, a stationary frame, a pair of secondary raceways, a rivet carrier positioned adjacent the lower end of each of said secondary raceways respectively and slidable vertically in said frame, a plunger in alignment with each of said carriers respectively and slidable vertically in said frame, an anvil in alignment with each of said plungers respectively, mechanism to impart a simultaneous reciprocatory movement to said plungers, and means to feed a rivet to each of said carriers from each of said secondary raceways during one cycle of movements of said plungers whereby said carrier may be moved downwardly by said plungers and said rivets driven out of the carriers and clinched against said anvils.

2. A twin rivet setting machine having, in combination, a primary raceway, a pair of secondary raceways, a rivet carrier positioned adjacent the lower end of each of said secondary raceways respectively, a plunger in alignment with each of said carriers respectively, an anvil in alignment with each of said plungers respectively, mechanism to impart a simultaneous reciprocatory movement to said plungers, a carrier slide extending transversely of said raceway and adapted to simultaneously receive a rivet from said primary raceway and deliver alternately another rivet to either one of said secondary raceways, and mechanism operated by said plunger reciprocating mechanism to impart a reciprocatory movement to said carrier slide.

3. A twin rivet setting machine having, in combination, a primary raceway, a pair of secondary raceways, a rivet carrier positioned adjacent the lower end of each of said secondary raceways respectively, a plunger in alignment with each of said carriers respectively, an anvil in alignment with each of said plungers respectively, mechanism to impart a simultaneous reciprocatory movement to said plungers, a carrier slide extending transversely of said raceways and adapted to simultaneously receive a rivet from said primary raceway and deliver another rivet to one of said secondary raceways, a lever connected to said slide, another lever 110 115 120 125 130

connected to said first-named lever and having an inclined edge thereon, and a contact member connected to said plungers and adapted to engage said inclined edge, whereby a reciprocatory movement may be imparted to said carrier slide.

4. A twin rivet setting machine having, in combination, a primary raceway, a pair of secondary raceways, a rivet carrier positioned adjacent the lower end of each of said secondary raceways respectively, a spring connected to each of said rivet carriers and acting to move them upwardly, a plunger in alignment with each of said carriers respectively, an anvil in alignment with each of said plungers respectively, mechanism to impart a simultaneous reciprocatory movement to said plungers, whereby a vertical reciprocatory movement may be imparted to said carrier slides, a carrier slide extending transversely of said raceways and adapted to simultaneously receive a rivet from said primary raceway and deliver another rivet to one of said secondary raceways, and mechanism operated by said plunger reciprocating mechanism to impart a reciprocatory movement to said carrier slide.

In testimony whereof I have hereunto set my hand.

30 WILLIAM E. BARTEL.
